(57) **CLAIM**

The ornamental design for a nozzle as shown and described.

DESCRIPTION

FIG. 1 is a back perspective view of a nozzle in accordance with my new design;

FIG. 2 is a back view of the nozzle of FIG. 1;

FIG. 3 is a front view of the nozzle of FIG. 1;

FIG. 4 is a right side view of the nozzle of FIG. 1;

FIG. 5 is a left side view of the nozzle of FIG. 1;

FIG. 6 is a bottom view of the nozzle of FIG. 1; and,

FIG. 7 is a top view of the nozzle of FIG. 1.

The broken lines in the drawings depict portions of the nozzle that form no part of the claimed design.
